UNITED STATES PATENT OFFICE.

HOMER J. TAYLOR, OF EAST LIVERPOOL, OHIO.

DESIGN FOR A PLATE OR SIMILAR ARTICLE.

48,425.

Specification for Design.

Patented Jan. 4, 1916.

Application filed September 28, 1915. Serial No. 53,148. Term of patent 3½ years.

To all whom it may concern:

Be it known that I, HOMER J. TAYLOR, a citizen of the United States, residing at East Liverpool, in the county of Columbiana and State of Ohio, have invented a new, original, and ornamental Design for a Plate or Similar Article, of which the following is a specification, reference being had to the accompanying drawing, forming part thereof.

The figure is a plan view of a plate showing my design.

I claim:

The ornamental design for a plate or similar article as shown.

HOMER J. TAYLOR.

Witnesses:

O. H. SEBRING,
FRANK F. GROFF.
